UNITED STATES PATENT OFFICE.

PERLEY R. GLASS, OF BROOKLINE, MASSACHUSETTS, ASSIGNOR TO UNITED SHOE MACHINERY COMPANY, OF PATERSON, NEW JERSEY, A CORPORATION OF NEW JERSEY.

GANG FASTENER-SETTING MACHINE.

1,191,885.

Specification of Letters Patent. Patented July 18, 1916.

Application filed June 5, 1911. Serial No. 631,264.

To all whom it may concern:

Be it known that I, PERLEY R. GLASS, a citizen of the United States, residing at Brookline, in the county of Norfolk and 5 State of Massachusetts, have invented certain Improvements in Gang Fastener-Setting Machines, of which the following description, in connection with the accompanying drawings, is a specification, like referring 10 to characters on the drawings indicating like parts in the several figures.

This invention relates to machines for simultaneously setting a series of fasteners in sheet material.

15 As herein shown, the invention is embodied in a machine for setting eyelets in boots and shoes, although many of its features may be advantageously embodied in machines for setting lacing hooks, studs or 20 other articles and the term "fasteners" is used hereinafter to designate all such articles.

An important feature of the invention 25 consists broadly in providing a gang fastener setting machine with automatically acting mechanism for spacing the various tools or instrumentalities, such as the setting dies and punches. Such mechanism renders the operation of a machine of this 30 type easy and convenient for the operator and adapts it for handling work in which it is necessary to set fastening devices in one piece with one spacing and in another piece with a different spacing. In another 35 aspect it is important because it simplifies the general construction of the machine in that it obviates the necessity of providing laterally adjustable raceways.

In a machine embodying the present invention the setting dies may be supplied 40 with fasteners while they are in a predetermined initial position and then the dies may be moved laterally in accordance with the required spacing carrying with them the 45 previously received fasteners. This construction is believed to be novel whether or not the spacing of the dies is effected automatically or otherwise.

In the machine herein shown there are provided oppositely disposed coöperating gangs 50 of tools, one gang being arranged to be spaced by manually operated means and the coöperating gang by automatically acting mechanism.

55 Another important feature of the inven-

tion consists in the provision of a single controlling device, such as a hand wheel or the like, whereby the tools of one gang may be spaced and the subsequent action of the automatic spacing mechanism for the coöperating gang also regulated. One manner in which these results may be effected consists in connecting the various tools of each gang to spacing disks, one of which may be turned manually and the other turned automatically by mechanism controlled in its movement by the position of the manually operated disk.

Other important features of the invention are found in the mechanical construction 70 and combinations by which the results above referred to are attained and these features will be pointed out more particularly hereinafter.

For the better grade of work it has been 75 found desirable to employ punching devices for perforating the work before the fasteners are set therein, said punching devices being distinct from the setting instrumentalities. Another feature of the invention, 80 accordingly, consists in providing a gang machine of the class described with punches arranged to operate in advance of the setting dies, said punches being arranged, however, for adjustment for spacing simultaneously with the setting dies. As herein shown, the male punches are arranged concentrically with the dies of one gang, while the punching dies and the other gang of setting dies are mounted in a head movable to 85 bring either gang into operative position.

Still other features of the invention relate to the raceway operating mechanism and consist in the provision of improved means for moving the raceway to and from delivering position, a device for holding the raceway in an inoperative position while the machine is at rest, and automatic means for releasing the raceway when the machine is started. As herein shown, the machine is 95 provided with means under the control of the operator for moving the raceway into position to be engaged by a latch and a cam operated lever is arranged to trip the latch and release the raceway when power is applied to the machine.

In the accompanying drawings, Figure 1 is a view of the machine in side elevation, partly in section; Fig. 2 is a view in front elevation showing clutch mechanism in 100 105 110

section and portions of the frame broken away; Fig. 3 is a plan view.

The frame 2 of the machine is provided with bearings for the driving shaft 4 which 5 extends transversely at the rear of the machine. On one end it is provided with a loosely mounted driving pulley 6 and a movable friction member 8 slideable on the shaft but held against relative rotation by means 10 of ribs or lugs 9 on the shaft which engage the corresponding ribs on the inner side of the friction member 8. The friction member is normally moved into clutching engagement with the driving pulley by means 15 of a spring 10 and is automatically disengaged when the treadle is released by the cam 12 acting through the cam lever 14, the link 16 and the shifting arm 18, the latter being connected with a loose ring 20 in 20 which turns the hub of the friction member. The link 16 is pivotally connected to the lower end of the cam lever 14 and has a lug 15 which engages a projection on the rear side of the shifting arm 18, being held 25 in engagement therewith by the spring 19. When it is desired to start the machine the link 16 is swung downwardly by the treadle rod 21 until the lug 15 disengages the projection on the shifting lever whereupon the 30 spring 10 is permitted to move the friction member toward the right into engaging position. On the release of the treadle rod 21 the spring 19 reestablishes effective connection and the operation of the machine continues until the action of the cam 12.

The punching dies 24 and upper setting dies 26 are mounted in a head 28 arranged for oscillation with a transverse pivot pin 30. The head is oscillated to move the 40 punching dies and setting dies alternately into operative position by a cam 32 on the main shaft acting through the bent rod 34 adjustably connected with an arm 36 extending upwardly and rearwardly from the pivot pin 30. For purposes of adjustment the arm 36 is slotted and the rod 34 is pivotally connected with a block 35 adjustably mounted in the slot. Adjustable stop pins 37 and 38 projecting through the frame of 45 the machine serve to determine accurately the two extreme positions of the head 28. The punching and setting dies are arranged in pairs in carriers 40 which are mounted for transverse movement in ways formed in 50 a block 42 removably held in the head 28 by a screw 43. Rigidly connected with one end of the pivot pin 30 and arranged to oscillate with the head 28 is a bracket 44 in which is journaled a spacing disk 46 having gear teeth formed on a part of its periphery. By setting this disk the spacing of the punching and setting dies may be 55 preliminarily determined. The spacing disk may be adjusted by turning the hand wheel 48 which carries a worm 50 meshing

with the gear teeth on the spacing disk. The stationary index 51 and graduations upon the spacing disk serve to indicate the spacing of the punching and setting dies.

The spacing disk 46 is connected with the 70 carriers 40 by means of a number of links 52 pivotally connected with the spacing disk and having forked ends arranged to engage trunnion pins on the respective carriers. Those links which are connected with the 75 carriers on one side of the center line are connected with the spacing disk at points above its axis and those which are connected with carriers on the other side of the center line are connected with the spacing disk at 80 points below its axis. By this construction rotation of the spacing disk in one direction serves to separate all the carriers from each other while rotation in the other direction correspondingly contracts them. For instance, in rotating the spacing disk 46 in a clockwise direction the carriers and dies mounted on the left of the center line will be pulled toward the center by the links connected with the spacing disk above its axis, 85 while those carriers on the right of the center line will be pushed toward the center by the links which are connected to the spacing disk below its axis.

Mounted for vertical reciprocation in ways 95 formed in the lower part of the frame 2 is a bifurcated head 60 in which are carried the lower setting dies 64. The head 60 is moved vertically by the eccentrics 66 on the main shaft 4 which act upon the rear ends of the 100 levers 67 pivotally mounted in adjustable eccentric bearings 68 on either side of the frame and connected at their forward ends to the head 60 by the links 70. A second similar bifurcated head 72 is mounted between the side portions of the head 60 to slide in ways formed in the frame and a T-shaped guideway is formed in the upper surface of its head in which are received the lower ends of the punches 62. The punches 110 extend concentrically through the lower setting dies and beside acting as punches also serve as spindles for engaging the eyelets in the lower ends of the raceways. At its upper end each punch is provided with a 115 stretching point and an annular punching surface, the stretching point serving to force the leather into the co-operating punching die in advance of the actual punching operation so that the hole punched out of the 120 stock will be of slightly greater diameter than the diameter of the body of the punch. Punching devices of this character are disclosed and claimed in United States Patent No. 921,648, granted May 11, 1909, to J. E. 125 McIntire. The head 72 is reciprocated by a cam 73 on the main shaft which acts upon the cam lever 74 connected at its forward end to the head 72 by a short vertical link 75.

The setting dies 64 are mounted for transverse movement in guideways in a block 76 which is removably held in position on the head 60 by a hinged clamping member 77 carrying a clamping screw 78. When it is desired to remove the die carrying block the screw 78 is loosened and a vertical pin 79 which serves as a retainer for the right end of the clamping member 77 is withdrawn permitting the clamping member to be swung forwardly about its left end. Each of the dies 64 is provided with a carrier having transverse trunnion pins, as in the case of the upper punching and setting die carriers and, as in that case, each of the carriers is connected by means of a transversely extending forked link 80 to a spacing disk 82, the latter being journaled in a bracket 83 rigidly connected with one side of the head 60. In the construction described it will be seen that the spacing disk 82 reciprocates vertically with the head 60. Controlling mechanism is provided for automatically effecting the spacing of the lower carriers in accordance with the predetermined spacing adjustment of the upper carriers. To this end the spacing disk 82 is arranged to be turned after the machine has been set in motion by a cam 84 on the main shaft 4. The cam 84 oscillates a horizontal rock shaft 86 by acting on a cam roller carried by the vertical rocker arm 87. At its forward end the rock shaft 86 is provided with an apertured head 88 in the forward end of which is formed a substantially vertical guideway for a slide block 90. Pivotally connected to the forward side of block 90 is a second block 91 fitted to slide in a vertical guideway formed in the slide 92. The two parts of the slide 92 are connected and held together by U-shaped members 81 extending from both upper and lower edges of the slide. The slide 92 is mounted for transverse reciprocation in ways formed in the back of the plate 93 which forms a part of the frame of the machine. On its left end, Fig. 2, the slide 92 is provided with a bracket or arm 94 having a vertical guideway formed therein. A block 95 is mounted in said guideway for sliding movement and is pivotally connected at its forward end to the back of the spacing disk 82 by a pin 96 which also serves as a wrist pin for the upper connecting link 80. It will be seen therefore that when the rock shaft 86 is oscillated the slide 92 will be moved horizontally and the spacing disk 82 will be turned by the block 95 which is carried by the bracket 94 of the slide. The vertical guideway in the arm 94 permits the block 95 to slide up and down as the disk 82 is moved vertically with the head 60 without interrupting the effective communication between the disk and slide 92.

The extent to which the spacing disk 82

is turned is controlled by the position of the upper spacing disk 46. To this end the upper spacing disk is provided at its lower side with a rearwardly extending pin 100 upon which slides a box 102 pivotally mounted between the arms of a yoke 104. The yoke 104, which constitutes the vertical arm of a bell crank lever fulcrumed on a horizontal spindle 106, is slidably received in a socket formed in the end of the horizontal arm 108. It will be seen that this connection permits the vertical arm of the bell crank lever to be oscillated when the spacing disk 46 is turned, the sliding connection permitting the necessary upward movement of the yoke 104 and the pivoted box permitting angular movement when the head 28 is oscillated. The horizontal arm 108 of the bell crank lever is connected to the rear side of the block 90 by means of a vertically extending link 110 so that the blocks 90 and 91 are moved farther from or nearer to the axis of the rock shaft 86 as the upper spacing disk 46 is turned.

It will be seen that when the blocks 90 and 91 are located in alignment with the rock shaft 86 there will be no bodily movement imparted to them, the block 90 merely oscillating about an axis coincident with that of the rock shaft, but when the blocks are moved out of alignment with this axis they will receive a bodily movement of oscillation which will be transmitted to the slide 92 and the lower spacing disk 82, as hereinabove explained. The rock shaft 86 is journaled in boxes formed in the upper ends of a pair of vertical standards 71 which are adjustably retained in ears projecting laterally from a shelf or bracket 61 secured to the right side of the machine.

The raceways 120 are formed on an inclined plate 122 which is pivotally supported upon the links 124 and 126. Normally the raceway is held in delivering position by means of a compression spring 128 which surrounds a horizontal rod 130 pivotally connected at its forward end to the link 126, the spring 128 bearing at its rear end against a block 132 mounted on the upper end of a cam lever 134. The raceways are retracted at the proper time in the cycle of the machine by a cam 136 on the main shaft acting upon a cam roller journaled on the arm 134. In order to permit the raceways to be retracted by the operator to allow them to become filled with eyelets there is provided a downwardly extending lug 138 on a plate 122 which stands in the path of one arm of a bell crank lever pivotally mounted in the frame of the machine and connected at its rear end to a treadle rod. The rod 130 is provided at its rear with a collar 142 which is engaged by a pivoted latch arm 144 when the raceways have been moved rearwardly to an inoperative position. The latch arm 144

is automatically tripped when the machine is set in operation by a tappet 146 on the upper end of the cam lever 134 whereupon the spring 128 will act to advance the raceways.

The raceways 120 are supplied with eyelets from a hopper 150 mounted upon the rear and upper end of the plate 122. Within the hopper there is rotatably mounted a brush or other suitable agitating or supporting device. In the machine herein shown a brush 152 is provided with a shaft 153 journaled in a boss formed in the plate 122 and provided with a grooved driving pulley 154. The pulley 154 is driven by means of a belt 155 running over idle pulleys journaled in a bracket 156 and driven by a grooved pulley 158 on the main shaft 4. The pulley 158 is formed in a cap 159 which fits over the elongated hub of the driving pulley 6 and is yieldingly connected therewith by a spring plunger 160. When it is desired to stop the rotation of the brush 152 the cap 159 may be drawn out of engagement with the locking plunger 160 by means of a handle on its outer end.

In operation the work to be eyeleted is placed upon a table and properly located relatively to the punches and dies by gages. In the drawings the table and gages have been omitted for the sake of clearness but their construction and arrangement may be substantially similar to those heretofore employed in gang machines of the class described. The spacing of the upper setting dies 26 and punching dies 24 is then adjusted to suit the work by turning the hand wheel 48 which shifts the carriers 40 through the connecting links 52. Turning the hand wheel 48 also rocks the bell crank lever 104, 108 and moves off center the block 90 in the head 88 of the rock shaft 86. During this time the raceways are in their forward position with their delivery ends over the lower setting dies and the agitating brush 152 is being rotated by the belt 155 driven from the loose member of the clutch.

When power is applied to the machine by depressing the treadle rod 21 the head 72 is elevated and each punch 62 impales one of the series of eyelets retained at the ends of the raceways. As soon as the eyelets have been engaged the raceways are retracted and the eyelets drawn out of them in the usual manner. When the raceways have been retracted the automatic spacing of the punches and lower sets is effected by the action of the cam 84 through the lower spacing disk 82, as already explained. The upward movement of the head 72 continues until the punches have entered the punching dies 24 and formed a line of perforations in the work. The head 72 is then slightly depressed to allow the upper setting dies 26 to be swung forwardly into opera-

tive position by the action of the cam 32 through the rod 34 and thereupon the heads 60 and 72 are elevated together, the punches acting as center spindles for the sets, and the eyelets are clenched by the dies 26 and 64. On the downward movement of the heads 60 and 72 the cam 84 swings the disk 82 reversely and the sets are moved laterally to their initial position.

Having thus described my invention, what I claim as new and desire to secure by Letters Patent of the United States is:

1. A machine of the class described having, in combination, oppositely disposed gangs of setting dies, and automatically acting mechanism for spacing the dies of one of said gangs.

2. A machine of the class described having, in combination, coöperating gangs of setting dies, a controlling device, and automatically acting mechanism controlled by said device for spacing the dies of one of said gangs.

3. A machine of the class described having, in combination, coöperating gangs of setting dies, means for supplying fasteners to the dies in one of said gangs, and automatically acting mechanism for spacing the dies in said gang after they have been so supplied.

4. A machine of the class described having, in combination, oppositely disposed gangs of setting dies, a plurality of raceways for supplying fasteners to the dies in one of said gangs, means for moving said raceways to and from delivering position, and automatically acting mechanism for spacing the dies in a gang after the raceways have moved from delivering position.

5. A machine of the class described having, in combination, coöperating gangs of setting dies, means for varying the spacing of the dies of one of said gangs, and means operating automatically for correspondingly spacing the dies of another gang.

6. A machine of the class described having, in combination, coöperating gangs of fastener-setting instrumentalities, means for changing the relative locations of the instrumentalities of one of said gangs, and means operating thereafter for correspondingly changing the relative locations of the instrumentalities of another gang.

7. A machine of the class described having, in combination, a gang of fastener-setting instrumentalities mounted for transverse movement from operative to inoperative position, a coöperating gang of fastener setting instrumentalities, a device for changing the relative locations of said instrumentalities of said first mentioned gang, and automatically acting mechanism controlled by said device for correspondingly changing the relative locations of the instrumentalities of the other gang.

8. A machine of the class described having, in combination, coöperating gangs of fastener-setting instrumentalities, means for supplying fasteners to the instrumentalities of one of said gangs, and mechanism operating after said instrumentalities have been so supplied for changing the relative locations thereof. 5
9. A machine of the class described having, in combination, a gang of setting dies movable transversely from operative to inoperative position, spacing mechanism bodily movable with said gang, and a co-operating gang of setting dies. 10
10. A machine of the class described having, in combination, a gang of setting dies movable transversely from operative to inoperative position, spacing mechanism bodily movable with said gang, a gang of setting instrumentalities coöperating with said gang of setting dies, and spacing mechanism for said instrumentalities controlled by the spacing mechanism first mentioned. 15
11. A machine of the class described having, in combination, a gang of punches and setting dies movable to bring the punches or dies alternately into operative position, spacing mechanism for simultaneously changing the relative locations of the punches and dies, a coöperating gang of punches and dies, and mechanism operating automatically for correspondingly changing the relative locations of the punches and dies of said coöperating gang. 20
12. A machine of the class described having, in combination, a gang of fastener-setting instrumentalities, raceways associated therewith, a spacing disk, connecting devices extending from different points on said disk to the separate instrumentalities of said gang, and means for turning said spacing disk to actuate the connecting devices. 25
13. A machine of the class described having, in combination, a gang of fastener-setting instrumentalities, raceways associated therewith, a spacing member mounted to turn about an axis and connecting links extending from points at different distances from the axis of said member to the separate instrumentalities of said gang. 30
14. A machine of the class described having, in combination, a gang of fastener-setting instrumentalities symmetrically disposed with respect to a center line, a spacing member mounted on a transversely extending axis at one side of said center line, and connecting links extending from points on the spacing member above its axis to the instrumentalities on one side of the center line and from points on the spacing member below its axis to the instrumentalities on the other side of the center line. 35
15. A machine of the class described having, in combination, an oscillatory head, 40
- a plurality of setting devices adjustably mounted therein, a spacing disk mounted to turn about an axis on said head and movable therewith, and connecting members extending between said spacing disk and the separate setting devices. 45
16. A machine of the class described having, in combination, coöperating gangs of setting devices, spacing disks connected respectively with each of said gangs, means for turning one of said disks to vary the relative location of the setting devices of one gang, and automatically acting mechanism for turning the other disk to vary correspondingly the location of the setting devices of the other gang. 50
17. A machine of the class described having, in combination, coöperating gangs of setting dies, means for supplying fasteners to the dies in one of said gangs, a spacing disk connected with each of said dies, and automatically acting mechanism for turning said spacing disk for spacing the dies after they have been so supplied. 55
18. A machine of the class described having, in combination, oppositely disposed gangs of setting dies, a plurality of raceways for supplying fasteners to the dies in one of said gangs, means for moving said raceways to and from delivering position, a spacing member connected with said setting dies, and automatically acting mechanism for spacing the dies in a gang after the raceways have moved from delivering position. 60
19. A machine of the class described having, in combination, coöperating gangs of setting dies, means for varying the spacing of the dies of one of said gangs, and means acting automatically for correspondingly spacing the dies of the other gang when the spacing of the dies of the first mentioned gang is more or less than a predetermined distance. 65
20. A machine of the class described having, in combination, coöperating gangs of setting dies, means for increasing the spacing of the dies of one of said gangs, and means acting automatically for spreading the dies of the other gang into alignment with those previously spread. 70
21. A machine of the class described having, in combination, coöperating gangs of fastener-setting devices, means for decreasing the spacing of the devices of one of said gangs, and means acting automatically for moving together the dies of the other gang so as to align with those already so contracted. 75
22. A machine of the class described having, in combination, a reciprocatory head, a setting device mounted thereon for transverse movement into different setting positions, a coöperating setting device arranged in operative relation to that first-mentioned in all operative positions thereof, and means 80
- 70
- 85
- 90
- 95
- 100
- 105
- 110
- 115
- 120
- 125
- 130

- movable with the head and operating automatically for changing the position of said setting device in the head.
23. A machine of the class described having, in combination, a frame, a setting device movable transversely of the frame, a head mounted for reciprocation toward and from said setting device, a coöperating setting device carried thereby and movable transversely therein, manually operated means for moving said first mentioned setting device, and means acting automatically to move said coöperating setting device into alinement therewith.
24. A machine of the class described having, in combination, coöperating gangs of setting devices, and mechanism for spacing the devices of one gang including a disk to which each device is connected, and a movable slide connected with said disk and arranged to turn said disk an amount proportional to its own movement.
25. A machine of the class described having, in combination, coöperating gangs of setting devices, mechanism for spacing the devices of one gang including a disk to which each device is connected, a slide connected with said disk, and power-operated means for imparting to said slide movements of varying extent.
26. A machine of the class described having, in combination, coöperating gangs of setting devices, mechanism for spacing the devices of one gang including a pivotally mounted member to which each device is connected, a slideway having a uniform oscillation, and means for connecting said pivotally mounted member with said oscillating slideway at variable distances from its axis.
27. A machine of the class described having, in combination, coöperating gangs of setting devices, mechanism for automatically spacing the devices of one gang including a pivotally mounted member to which each setting device is connected, a block attached to said member, a reciprocatory slide having a guideway in which said block is received, an oscillatory rock shaft having operative connection with said reciprocatory slide, and an actuating cam for said rock shaft.
28. A machine of the class described having, in combination, coöperating gangs of setting devices, a movable head in which one of said gangs of setting devices is mounted, and mechanism for spacing said setting devices including a disk pivotally mounted on said head and movable therewith, a reciprocatory slide having a guideway extending parallel to the path of movement of said head, a connecting member attached to said disk and sliding in said guideway during the movement of said head and disk, and means for imparting movements of varying extent to said slide.
29. A machine of the class described having, in combination, a gang of setting devices movable vertically to set a plurality of fasteners, and spacing mechanism therefor including a slide having operative connection with said setting devices, said slide being guided for horizontal movement but at all times being held against vertical movement.
30. A machine of the class described having, in combination, a reciprocatory head carrying a gang of setting devices, and spacing mechanism therefor including a stationary guideway extending at right angles to the path of movement of said head, a slide mounted in said guideway for reciprocation, and connecting mechanism between said slide and said setting devices.
31. A machine of the class described having, in combination, a reciprocatory head carrying a gang of setting devices, an oscillating head carrying a coöperating gang of setting devices, spacing mechanism for said latter gang of setting devices, and a controlling disk carried by said oscillating head and having at all times an operative connection with said spacing mechanism.
32. A machine for setting fasteners in the uppers of boots and shoes, having in combination, a series of fastener supplying raceways spaced from each other, a series of setting devices also spaced from each other, and automatically acting mechanism for spacing the members of one of said series after the setting devices have been supplied by the raceways.
33. An eyeleting machine having, in combination, coöperating gangs of tools for operating upon sheet material, means for varying the spacing of the tools in one of said gangs, and automatically acting mechanism for correspondingly spacing the tools of the other gang.
34. A machine of the class described having, in combination, coöperating gangs of tools for operating on sheet material, means for increasing the spacing of the tools in one of said gangs, and means acting automatically thereafter for spreading the tools of the other gang into alinement with those previously spread.
35. A machine of the class described having, in combination, an oscillatory head carrying a punch and setting die, a reciprocatory block carrying coöperating members, and means for oscillating said head comprising a slotted arm, a cam rod adjustably connected therewith, and an actuating cam for said rod.
36. A machine of the class described having, in combination, a frame, coöperating gangs of tools for operating on sheet material mounted therein, spacing mechanism for the tools in one of said gangs, a rock shaft for operating said spacing mechanism, and

separate bearing members for said rock shaft independently sustained by said frame.

37. A machine for setting fasteners in the uppers of boots and shoes, having in combination, a series of fastener supplying raceways spaced from each other, a series of setting devices also spaced from each other, an upsetting die arranged to coöperate with each setting device, manually operated means for spacing said upsetting dies, and automatically acting mechanism for spacing the members of one of said series.

38. A machine of the class described having, in combination, fastener setting devices, an oscillating raceway movable from an inoperative position to a fastener delivering position, manually operated means for moving said raceway from one position to the other, a spring, and automatic mechanism arranged to permit said spring to return the raceway to its other position automatically when the machine is started.

39. A machine of the class described having, in combination, a punch, a concentrically arranged setting die, separate means for actuating said punch and die to perforate the work and set a fastener therein, and a device for moving simultaneously said punch and die laterally during their acting movement.

40. A machine of the class described having, in combination, a gang of punches, a setting die arranged concentrically of each punch, independent means for actuating said punches and said dies, and spacing mechanism for adjusting each pair of punches and dies simultaneously.

41. A machine of the class described having, in combination, a reciprocatory head, a gang of punches adjustably mounted in said head, a second reciprocatory head, a gang of setting dies adjustably mounted in said second head, and means for simultaneously moving each of said punches and dies in their respective heads to vary their spacing.

42. A machine of the class described having, in combination, a reciprocatory head, a gang of punches adjustably mounted in said head, a gang of setting dies disposed concentrically with said punches, an oscillatory head carrying punching dies and setting dies, means for advancing said reciprocatory head to force the punches into the punching dies and then to retract the punches, means operating thereafter to swing said oscillatory head to bring said setting dies into operative relation with said concentric setting dies, and means for advancing said latter dies to clench a series of eyelets.

43. A machine of the class described having, in combination, a movable head 28 carrying a punching die and a setting die, a punch-carrying head 72, a set-carrying head

60, means for moving the head 28 from one position to another to render the punching die and setting die alternately operative, and means for actuating the punch-carrying head 72 when the movable head 28 is in one position and the set carrying head 60 when the movable head 28 is in the other position.

44. A machine of the class described having, in combination, coöoperating gangs of setting devices, coöoperating gangs of punching devices arranged for operation prior to the operation of said setting devices, and automatic mechanism for spacing the setting devices of one gang and the punching devices of one gang.

45. A machine of the class described having, in combination, coöoperating gangs of tools, actuating means therefor, other coöoperating gangs of tools arranged for subsequent operation, and means for automatically spacing the tools in two of said gangs.

46. A machine of the class described having, in combination, a gang of setting dies movable simultaneously in parallel paths from operative to inoperative position and also movable toward and from each other for spacing, spacing mechanism bodily movable with said gang in its movement from operative position, and a coöperating gang of setting dies.

47. A machine of the class described having, in combination, a gang of setting dies movable as a gang about a fixed axis to and from operative position, the separate dies being individually movable for spacing, spacing mechanism movable bodily with the dies when they are moved as a gang, and a coöperating gang of setting dies.

48. A machine of the class described having, in combination, a pair of coöoperating gangs of setting dies, means for relatively moving said gangs to effect the setting operation, and mechanically actuated spacing mechanism timed for spacing the dies of one gang after the machine has been set in motion and preliminarily to the setting operation.

49. A machine of the class described having, in combination, oppositely disposed gangs of setting dies, and automatically acting mechanism for changing the spacing of the dies of one of the gangs from a predetermined initial spacing to a controllable setting spacing.

50. A machine for setting fasteners in the uppers of boots and shoes, having in combination, a gang of fastener carrying devices, a coöperating gang of upsetting dies, raceways for supplying fasteners to the carrying devices of the gang, and means constructed and arranged to be operated after the carrying devices have been so supplied and prior to the setting operation for spacing the carrying devices.

51. A gang fastener setting machine hav-

ing, in combination, coöperating gangs of setting dies relatively movable toward and from each other, and mechanism for spacing the dies of one gang during the relative 5 movement of the gangs.

52. A gang fastener setting machine having, in combination, a gang of upsetting dies, a gang of fastener carrying dies movable toward and from the gang of upsetting dies, 10 and mechanism for spacing the fastener carrying dies during their movement as a gang with respect to the upsetting gang.

53. A gang fastener setting machine having, in combination, a punching device and 15 setting die concentrically arranged, a coöperating punching device and a coöperating setting die arranged side by side, and means for moving the latter elements transversely to bring them alternately into operative re-

lation with one or other of the concentrically 20 arranged elements.

54. A gang fastener setting machine, having, in combination, a gang of upsetting dies, a gang of fastener carrying members movable toward and from the gang of upsetting dies, and means for spacing the upsetting dies of the gang, the fastener carrying members being subsequently and automatically spaced to correspond to the spacing of the upsetting dies. 30

In testimony whereof I have signed my name to this specification in the presence of two subscribing witnesses.

PERLEY R. GLASS.
